ATTORNEY

UNITED STATES PATENT OFFICE.

HARRY HIGHAM, OF NEWARK, NEW JERSEY.

OXFORD EYEGLASSES.

Application filed June 14, 1926. Serial No. 115,810.

This invention relates to the so-called Oxford type of eye-glasses, i. e., eye-glasses in which each lens frame is attached by a spring-pivot connection to one end of an approximately straight plate-spring or elastic bridge connecting the lens frames and the instrument is therefore adapted to be folded when not in use so that the lens frames are opposed to and substantially register with each other, being then locked in this position by a spring-catch on a handle projecting from one of the frames engaging a lug or notch on the other. Such eye-glasses are of course provided also with nose-guards or nose-clips, and it is necessary that in the folding and unfolding these parts should pass each other without preventing the completion of the movement and with as little interference as possible. Usually each nose-clip consists of a pad formed with a projecting supporting arm which is attached to the corresponding lens frame, and in the construction heretofore known (see the Hutton et al. Patent #1,016,153, for example) this arm was not only short but it joined the pad at the forward side thereof, which construction possessed the fault that it very much limited the possibility by bending the arm for fitting the instrument to suit each particular wearer and in many cases required the entire removal of the arm from the lens frame in order to either shorten or lengthen it.

My object by the present invention is to provide a pair of eye-glasses of the type indicated with nose-clips which, while permitting the folding and unfolding of the instrument without undue interference of the nose-clips with each other, shall be so constructed that adjustment thereof for every possible condition may be accomplished simply by readily effected bending operations.

In the drawing,

Fig. 1 is a fragmentary rear view of a pair of Oxford eye-glasses embodying my invention, the same showing one lens frame and its nose-clip;

Fig. 2 is an inside elevation of what is seen in Fig. 1;

Fig. 3 is a fragmentary plan of the lens frame and nose-clip shown in Fig. 1;

Fig. 4 is a rear elevation of the improved eye-glasses; and

Fig. 5 shows the blank from which a nose-clip according to this invention is made.

Each lens frame 1, plate-spring or elastic bridge 2 having spring-pivot connections 3 with the lens frames, the handle 4 projecting from one lens frame, and the spring catch 5 on said handle adapted to engage a lug or notch 6 on the other lens frame are or may be all substantially the same as in the patent above mentioned.

Each nose-clip according to this invention includes a pad 7 which in general may have the same form as the known pad used in this class of eye-glasses, being a loop-shaped piece of metal arranged in a front-to-rear plane and having a convex rear edge 7^a and its forward edge formed with a salient angle 7^b, but this particular form of the pad is not especially material. Projecting from the pad at its rearward portion and centrally of its convex side is an arm or post 8 which is bent off from and forwardly with respect to the pad. This arm is attached permanently to the corresponding lens frame, as by brazing it thereto and at about the position shown in the drawing.

In order to form the nose-clip the pad and arm may be stamped from a single piece of sheet metal, at which time said pad and arm would lie in the same plane (Fig. 5). After the part is stamped out the arm will then be bent off into that relation to the pad which has above been indicated. By following this method the pad and arm will be integral, thus reducing the possibility of breakage at their point of juncture if any bending is to be done in that vicinity in fitting the glasses to the wearer. I note further that the arm 8 affords at 8^a a bend presenting a rearwardly convex curved surface which is rearward of the pad and in effect forms a camming surface for a purpose to appear.

Since the arm or post 8 projects from the rear portion of the pad instead of from its forward portion it is desirably longer than the arm of the known construction, and in view of this and its relation to the pad (flanking the same) there is permitted much wider range of adjustment of the pad by bending the arm, and moreover the arm will undergo considerable bending without breakage or unduly straining any of the

parts. Thus the two nose-clips can be adjusted toward or from each other, forward and back, up and down or to different angularity on various axes to a practically unlimited variety of positions so as to suit the facial conditions and also effect a proper centering of the lenses and the correct pupillary distance thereof from the wearer's eyes. Such adjustments are all possible simply 10 by bending each or both of the nose-clips, and in no case is removal of either arm from the lens frame necessary.

At the same time the folding and unfolding operations are possible without undue 15 interference of the nose-clips with each other, nor can they accidentally be caught on each other at that step in the folding or unfolding movement when they are in a partly folded condition. This is principally 20 because each arm at 8^a is developed as a hump, projecting rearward of the pads, which if the front edge of one nose-clip would otherwise catch on the rear edge of

the other, serves to cam or fend it off and so prevent an interlock. 25

Having thus fully described my invention what I claim and desire to secure by Letters Patent is:

Folding eye-glasses of the class specified including a pair of lens frames, an elastic bridge having a spring-pivot connection with each frame, and nose-clips for the respective frames each consisting of a pad arranged to lie in a front-to-rear plane and an arm projecting rearwardly from the rear portion of the pad and bent forwardly and being rigidly secured to the corresponding lens frame, said arm adjacent the bend being formed with a rearwardly convex hump, said hump being adapted to cam off the forward portion of the opposite nose pad on contact of said nose clips in passing each other when the eye glasses are folded or unfolded. 35 40

In testimony whereof I affix my signature.
HARRY HIGHAM.
